MACHINE FOR FORMING BRIQUETTES

Filed Oct. 24, 1927

UNITED STATES PATENT OFFICE

JOHN O. NAVONE, OF EMERYVILLE, CALIFORNIA

MACHINE FOR FORMING BRIQUETTES

Application filed October 24, 1927. Serial No. 228,221.

The invention relates to machines for forming briquettes, or the like.

The principal object of the invention is to provide a machine in which coal dust or the refuse of gas generators or the like, that still contains some fuel value, may be readily compressed into briquettes of such a size and shape as to fit a fireplace.

Another object of the invention is to provide a machine for forming briquettes which is simple in construction, positive in operation, and permits sufficient resiliency of movement as to prevent the mixing and compressing of the clinkers with the compressible coal dust or the like.

A still further object of the invention is to provide a machine for forming briquettes of equal size and weight and approximately of equal density. Said briquette-forming machine is so constructed as to compress the damp refuse material or coal dust that remains in a gas generator after the production of gas into semi-cylindrical briquettes.

Another object of the invention is to provide a briquette-forming machine which is highly useful and simple in construction. Convenience of arrangement and comparative inexpensive of manufacture are further objects which have been borne in mind in the production and development of the invention.

Other objects of the invention, together with the foregoing, will be set forth in the following description of the preferred embodiment of means for practicing the same, which is illustrated in the drawing accompanying and forming part of the specification. It is to be understood that I do not limit myself to the embodiment disclosed in said description and the drawings, as I may adopt variations of my preferred form within the scope of my invention, as set forth in the claims.

In the drawings:—

Figure 1 is a side elevation of my device showing the general arrangement of parts therein.

Figure 2 is a section taken on the line 2—2 of Figure 1; and

Figure 3 is a perspective view of a completed briquette.

In the accompanying drawing, the reference numeral 1 indicates a supporting frame. A wheel 2 is rotatably mounted on the frame by means of an axle 3. Flanges 4 are secured to the opposite sides of the wheel 2 by means of bolts 5 and nuts 6. The flanges extend beyond the periphery of the wheel 2, as it is clearly shown in Figure 2, and form a channel 4' for the purpose to be hereinafter described. It is to be noted that the width of the channel 4', formed by the flanges 4, may be adjusted to a certain extent by the loosening or tightening up of the bolts 5 and the nuts 6. A second wheel 7 is secured on an axle 9, said axle being eccentrically and rotatably mounted in bearings 8 which bearings, in turn, are adapted to be rotated in the frame 1.

The first wheel 2 and the second wheel 7 are in axial alignment when assembled. Semi-cylindrical grooves 10 are provided on the outside periphery of the wheel 7. The semi-cylindrical grooves 10 extend transversely on the periphery of said wheel and are disposed, side by side, divided by a narrow edge. The distance between the axle 3 and the axle 9 is so determined that the wheel 7 is supported in such a relation that the semi-cylindrical grooves 10 thereon extend into the channel 4' on the wheel 2. The wheels are rotated by any conventional means, and the power is transmitted to a gear 11 and a gear 12 which, in turn, rotate gears 13 and 14 secured respectively to the axles 9 and 3. It is to be noted that the wheels 2 and 7 are rotated in opposite directions as it is indicated by the arrows in Figure 1. The coal dust, or similar material, is fed into a hopper 15 supported on the frame 1, and it is discharged therefrom into the channel 4' between the flanges 4. After the coal is discharged on the periphery of the wheel 2, it is carried thereby in the direction of the arrow toward the wheel 7.

The wheel 7 is rotated in a counter-clockwise direction, and the transverse cylindrical grooves 10 thereon gradually approach the periphery of the wheel 2, thereby gradually pressing the coal dust or like material into the semi-cylindrical shape as shown in Figure 3. The further rotating of the wheels 2 and 100

7 results in the discharging of the briquettes 16 upon a conveyor, not shown, which may be disposed below the wheels 2 and 7 so as to carry the briquettes 16 to any point desired. 5 In order to prevent the coal dust or similar substance falling out of the channel 4' over the flanges 4, while it is carried toward the horizontal axis of the wheel, a plate 17 is provided. Said plate 17 is pivotally supported in a bracket 18 which, in turn, is pivoted to the frame 1. The plate 17 is arcuate in shape and covers a portion of the channel, thereby slightly compressing the coal dust before it reaches the semi-cylindrical transverse 10 grooves 10. The pressure exerted by the arcuate-shaped plate 17 on the coal dust may be readily adjusted by a set screw 19 extending thru a lug 20, being integral with the bracket 18. It is evident that the turning of 15 the set screw 19 readily regulates the position and the pressure of the arcuate plate 17 upon and relative to the substance in the channel 4'.

A scraper 21 is secured to the frame 1 so as 20 to assume a tangential position relative to the periphery of the wheel 2 in order to scrape all the coal dust or other material that may adhere thereto.

In order to prevent the pressing of any 25 clinker or other rocky or hard substance into the briquettes and to obviate any danger of damage to the machinery by such hard rocks or clinkers mixed with the coal dust, I provide a safety mechanism for automatically 30 changing the distance between the center of the wheels so as to permit the elimination of the hard rocks or clinkers or large masses of hard material from between the wheels. A bar 22 is pivotally secured at one end to the 35 axle 9 of the wheel 7. The other end thereof is pivotally secured to a link 23 which, in turn, is pivotally secured to a supporting member 24. A coil spring 25 surrounds the supporting member 24 and the link 23 and it tends to maintain the same in a relatively 40 perpendicular or upright position, thereby maintaining the axle 9 in a position above the center of the bearing 8 and on the vertical center line thereof as shown in Figure 1. 45 When any clinker or rock tends to clog the machinery by being forced between the wheel 2 and the wheel 7, the wheel 7 and the axle 9 are forced to swing outwardly away from 50 the wheel 2. The bearing 8 is caused to turn in the frame 1, by the eccentric movement of the axle 9, whereby the rod 22 is advanced 55 outwardly and swings the link 23 against the action of the coil spring 25. Thus, sufficient clearance is provided between the 60 wheels to permit the release of the clinker or rock therefrom. After the obstruction is removed, the action of the coil spring 25 returns the link 23, the bar 22, and the axle 9 65 to their original positions, thereby maintain-

ing the wheels 2 and 7 in the operative position heretofore described.

It will be recognized that a particularly simple device is provided to accomplish the forming of briquettes from the inferior materials which otherwise would go to waste; and that this machine combines ready adjustment and an automatic action with a ruggedness of construction and readiness of operation, especially adapting it for its use. 70 Being a unitary character, the device requires no careful setting up and lends itself to effective application by the labor ordinarily available. 75

Having thus described my invention, what 80 I now claim as novel and desire to secure by Letters Patent is:

1. A briquette-forming machine comprising a frame, a wheel being rotatable in said frame and having a channel on the outside periphery thereof, bearings rotatable in the frame, a form wheel having form grooves on the outside periphery thereof in coacting relation with said channel, and being eccentrically and rotatably mounted in said bearings, 85 said wheel and said form wheel being rotated in opposite directions to each other, and resilient means to hold the bearings against rotation and to allow the swinging of the form wheel around the center of the bearings so as 90 to change the clearance between said grooves and said channel.

2. A briquette-forming machine comprising a frame, a wheel being rotatable in said frame and having a channel on the outside 100 periphery thereof, a form wheel being rotatable in said frame and having form grooves on the outside periphery thereof in coacting relation with said channel, said wheel and said form wheel to be rotated in opposite directions to each other, resilient 105 means to automatically change the clearance between said grooves and said channel, and adjustable means for retaining a material in said channel on the downward travel thereof. 110

3. A briquette-forming machine comprising a frame, a wheel being rotatable in said frame and having a channel on the outside periphery thereof, a form wheel being rotatable in said frame and having form grooves on the outside periphery thereof in coacting relation with said channel, said wheel and said form wheel to be rotated in opposite directions to each other, resilient 115 means to automatically change the clearance between said grooves and said channel, adjustable means for retaining a material in said channel on the downward travel thereof, and a scraper on said frame tangentially disposed relative to said wheel. 120

4. A briquette-forming machine comprising a frame, a wheel being rotatable in said frame and having a channel on the outside periphery thereof, a form wheel having form 125

grooves on the outside periphery thereof in coacting relation to said channel, means rotatable in the frame for rotatably supporting said form wheel, said form wheel being eccentrically mounted on said means, and resilient means for holding said eccentric means against rotation so as to permit the momentary rotation of said supporting means and the swinging of said form wheel away from said channel.

5. A briquette-forming machine comprising a frame, a wheel being rotatably supported in said frame and having a channel on the outside periphery thereof, a form wheel having form grooves transversely disposed on the outside periphery thereof, said wheel and said form wheel to be rotated in opposite directions, thereby tangentially passing said grooves into and out of said channel, and bearings in said frame for rotatably supporting said form wheel, said form wheel being eccentrically mounted in said bearings and being resiliently held against swinging around the center of the 20 bearings.

6. A briquette-forming machine comprising a frame, a wheel being rotatably supported in said frame and having a channel on the outside periphery thereof, a form wheel having form grooves transversely disposed on the outside periphery thereof, said wheel and said form wheel to be rotated in opposite directions, thereby tangentially passing said grooves into and out of said channel, bearings 25 eccentrically and rotatably mounted in said frame for rotatably supporting said form wheel, resilient means for maintaining said bearings in position so as to permit the momentary swinging of said form wheel and a said bearing away from said channel, and a plate pivotally and adjustably secured to said frame for retaining the material in said channel.

7. A briquette-forming machine comprising a frame, a wheel being rotatably supported in said frame and having a channel on the outside periphery thereof, a form wheel having form grooves transversely disposed on the outside periphery thereof, said wheel and said form wheel to be rotated in opposite directions, thereby tangentially passing said grooves into and out of said channel, bearings eccentrically and rotatably mounted in said frame for rotatably supporting said form wheel, resilient means for maintaining said bearings in position so as to permit the momentary swinging of said form wheel and a said bearing away from said channel, a plate pivotally and adjustably secured to said frame for retaining the material in said channel, and a scraper on the frame tangentially disposed to said wheel.

8. A briquette-forming machine comprising a frame, a wheel being rotatably supported in said frame and having a channel on the out-

side periphery thereof, a form wheel having form grooves transversely disposed on the outside periphery thereof, said wheel and said form wheel to be rotated in opposite directions, thereby tangentially passing said grooves into and out of said channel, bearings eccentrically and rotatably mounted in said frame for rotatably supporting said form wheel, resilient means for maintaining said bearings in position so as to permit the momentary swinging of said form wheel and a said bearing away from said channel, a plate pivotally and adjustably secured to said frame for retaining the material in said channel, a scraper on the frame tangentially disposed to said wheel, and a hopper on the frame opposite said channel.

9. A briquette-forming machine comprising a frame, a wheel being rotatably supported in said frame and having a channel on the outside periphery thereof, a form wheel having form grooves transversely disposed on the outside periphery thereof, said wheel and said form wheel to be rotated in opposite directions, thereby tangentially passing said grooves into and out of said channel, bearings rotatably mounted in said frame, said form wheel being eccentrically and rotatably mounted in said bearings, a rod pivotally secured around the center of the form wheel, a link pivotally secured to the free end of said rod, a standard pivotally supporting said link, and resilient means to maintain said link in an upright position relatively to said standard.

10. A briquette-forming machine comprising a frame, two coacting mold wheels having peripheral molds rotatably mounted on said frame, gears for driving the said wheels, one of said wheels being movably mounted on said frame, the line of movement thereof being arcuate, and resilient means for normally holding said wheel in a fixed position.

11. A briquette-forming machine comprising a frame, two coacting mold wheels having peripheral molds rotatably mounted on said frame, gears for driving the said wheels, one of said wheels being eccentrically journaled in a rotatable bearing, to compensate for an excess of material in the molds, and resilient means for normally holding said wheel in a fixed position.

In testimony whereof I affix my signature.

JOHN O. NAVONE. 126
